UNITED STATES PATENT OFFICE.

CHARLES R. HAMMAN, OF SPRINGFIELD, OHIO.

DESIGN FOR A COMMODE.

SPECIFICATION forming part of Design No. 24,687, dated September 17, 1895.

Application filed February 21, 1895. Serial No. 539,285. Term of patent 7 years.

To all whom it may concern:

Be it known that I, CHARLES R. HAMMAN, a citizen of the United States, residing at Springfield, in the county of Clark and State 5 of Ohio, have invented a certain new and original Design for Commodes, of which the following is a specification, reference being had therein to the accompanying drawing.

In the accompanying illustration the figure o is a perspective view of the commode, showing my design.

My design consists in a cube A D, with a back B' and elevated sides having edges E', which, with the edges F of the sides G, form 5 ogee curves. The base J of the sides G has a

molding K L, corresponding with the molding of the cube. The side D of the cube has an opening and the base J has a similar-shaped opening filled by the surface M.

Having thus fully described my invention, 20 what I claim as new, and desire to secure by Letters Patent, is—

The design for a commode herein shown and described.

In testimony whereof I affix my signature 25 in presence of two witnesses.

CHARLES R. HAMMAN.

Witnesses:

OLIVER H. MILLER,
W. M. MCNAIR.
